CLAIM

The ornamental design for a cap, as shown and described.

DESCRIPTION

FIG. 1 is a top perspective view of a first embodiment of a cap, showing the new design.

FIG. 2 is a top plan view thereof.

FIG. 3 is a bottom plan view thereof.

FIG. 4 is a front elevational view thereof. The rear elevational view is the same as the front elevational view; and, FIG. 5 is a perspective view of the bottom of the cap in an inverted position relative to FIGS. 1-4.

The shading shown in the figures is provided merely to illustrate the contour of the new design; it is not intended to be indicative of any particular texture. The cap may be useful for covering inlet ports on a full-face respirator.
